United States Patent Office.

WILLIAM TEAMER, OF EVANSVILLE, INDIANA.

Letters Patent No. 105,384, dated July 12, 1870.

IMPROVEMENT IN STOVE-GRATES.

The Schedule referred to in these Letters Patent and making part of the same.

I, WILLIAM TEAMER, of Evansville, county of Vanderburg, State of Indiana, have invented certain Improvements in Stoves, Heaters, &c., of which the following is a specification.

Nature and Object of the Invention.

My invention consists mainly of a revolving fire-basket, or grate, arranged adjacent to the oven of a stove or range, &c., as fully described hereafter, the advantages of the arrangement being economy in and thorough consumption of fuel, a perfect radiation of heat, and the facility afforded for raking the fire at any part of the grate, on turning the latter.

Description of the Accompanying Drawing.

Figure 1 is a vertical sectional view of sufficient of a cooking-stove to illustrate my improvements;

Figure 2, a sectional plan view of the same on the line 1 2, fig. 1; and

Figure 3, a detached view.

General Description.

A represents the depressed hearth-plate of a cooking-stove;

B, C, and D, the front, top, and side plates of the same;

F, the oven;

G, the fire-place; and

a and b, flues above and below the oven, communicating with the fire-place, and leading to the outlet-pipe.

The grate H is made in the form of a cylindrical casing or basket, open at the top, and supported at the bottom only by a horizontal cross-bar, J, which extends across and is fitted at its opposite ends into recesses e e of the depressed hearth-plate, as best observed in fig. 3.

The grate is provided with a projection or journal, d, which passes through the rest or supporting-bar J, this enabling the grate to revolve freely upon the said bar, but it is prevented from being accidentally lifted from the same by a pin or other fastening device, e, which is passed through the journal.

The revolving grate is contained partly within the fire-place, and partly within a frame, M, secured to the front plate of the stove, and forming an extension of the fire-place, the said frame, as well as the fire-plate P secured to the front of the oven, being furnished with lugs i, which serve to steady the grate at

the top, and to thus relieve the strain upon its journal d.

Sliding doors x and hinged doors y, indicated by dotted lines in the drawing, are intended to be placed above and in front of the revolving grate, the doors x to be opened when the grate is to be replenished with fuel, and the doors y when it is to be raked.

It will be observed, on reference to fig. 1, that the grate is arranged at so low a point that the heated products of combustion can be directed through either of the flues a or b, above or beneath the oven, according to the adjustment of the dampers in the said flues.

The principal advantages arising from the use of my improved revolving grate are that ready access can be had to any portion of the same, for the purpose of raking the fire, while less fuel is required, and a more perfect combustion and radiation of heat obtained than in ordinary arrangements, where the fuel is in contact with solid plates, at the sides and back of the stove or fire-place.

In order to protect the plates of the stove from the effects of the great heat radiated from the basket-grate, I propose to line the interior of the same, especially the fire-plate P and doors x, with hydraulic cement.

Although I prefer that the revolving grate should be cylindrical and vertical, as above described, it will be evident that it may be conical, or slightly inclined, without departing from the main features of my invention.

Claims.

1. The revolving grate or fire-basket H, arranged within a stove or range adjacent to the oven, so as to radiate heat toward the same, as described.
2. The combination of the revolving fire-box H, the oven F, upper flue a, and lower flue b, for the purpose specified.
3. The said fire-basket projecting beyond the front plate B, in combination with doors x y, arranged as described.

In testimony whereof I have signed my name to this specification in the presence of two subscribing witnesses.

WILLIAM TEAMER.
